UNITED STATES PATENT OFFICE

ROBERT L. BLANDING, OF PROVIDENCE, RHODE ISLAND

WATER HEATER

Application filed June 7, 1929. Serial No. 369,226.

The present invention relates broadly to the art of heat interchange, and more particularly to this art as applicable to the utilization of boiler water for producing an abundant supply of hot water for domestic purposes.

There is a continually increasing demand for a house heating system of such nature that it may be effectively utilized for furnishing at all times an ample supply of clean hot water for domestic consumption. In many cases it is necessary to provide not only chamber or non-sectional boilers, but sectional boilers with attachments effective for producing an indirect heat interchange between the boiler water and the domestic water supply for bringing such supply to the required temperature. Installations as heretofore provided for this purpose have been more or less complicated, expensive, and difficult to install due to the number of connections required.

In accordance with the present invention, there is provided a combined house heating and domestic water heating system of an inexpensive nature requiring a minimum number of connections and operating effectively not only to increase the efficiency of the boiler itself, but also improving the operation thereof as well as the effectiveness of the burner installation utilized for heating the same.

In the accompanying drawings, there are shown for purposes of illustration only, certain preferred embodiments of the present invention.

In the drawings:—

Figure 1 is a partial side elevational view, partly broken away, illustrating more or less diagrammatically one form of installation in accordance with the present invention;

Figure 2 is an end elevational view of the installation illustrated in Figure 1;

Figure 3 is a detail sectional view on an enlarged scale along the line III—III of Figure 1, looking in the direction of the arrows, this figure being partly broken away for purposes of a clearer understanding of the structure involved;

Figure 4 is a view, similar to Figure 1, but

illustrating another embodiment of the invention;

Figure 5 is a detail sectional view, on an enlarged scale, along the line V—V of Figure 4, looking in the direction of the arrows; and

Figure 6 is a detail sectional view on an enlarged scale, of one of the combined headers and water connecting lines for the indirect heater.

In accordance with the embodiment of Figures 1 to 3 of the present invention, there may be provided a boiler 2 of the single chamber type, operatively supported in the desired relationship to a combustion chamber 3, effective for bringing the water in the boiler to the desired temperature.

It is a well-known fact that in boiler systems of this general character, the hottest water is adjacent the water line of the boiler, such water line being indicated in Figures 1 and 2, in chain lines.

Disposed laterally of the boiler and adjacent the water level in the water chamber thereof, is a water heater 4. This heater comprises an outer shell of any desired dimensions, having positioned and arranged therein any desired number of tubes 5, preferably of copper, having a comparatively high co-efficient of heat transfer. As illustrated more particularly in Figure 6 of the drawings, the tubes, all of which are of generally U-shape, as indicated in dotted lines, for example, in Figure 4, each have one end secured to a tube plate 6 below the center line thereof and the opposite ends secured to the tube plate above the center line. The tube plate in turn cooperates with the connection 7, having a central partition 8 abutting against the tube plate and forming a header whereby water entering through the inlet 9 is caused to enter one end of all of the tubes simultaneously, the water after passing through the tubes being discharged through the outlet connection 10. For the purpose of preventing any trapping of air within the tubes, or within the header, the partition 8 may be provided with a relatively small bleeder or bypass opening 11, permitting the free escape of any trapped air.

Cooperating with the heater 4 is a storage

100

tank 12 for the storage of domestic heating water, this tank having an inlet 13 for cold water, and the outlet 14 for conveying hot water to the point of use.

5 It is also provided with a circulating connection 15 for conveying water from the storage tank to the inlet connection 9 of the heater, and with a second circulating connection 16 communicating with the outlet connection 10 of the heater for conveying heated water into the tank. The connections described provide a thermo-siphon circulating system of such nature that upon the application of sufficient heat to the tubes 5, there will be maintained at all times a supply of clean hot water in the storage tank 12 available for use as desired.

Heating of the water in the tubes 5 is accomplished by indirect heat transfer, the water for heating purposes being supplied directly from the water chamber of the boiler 2 into the space around the tubes 5 by one or more connections 17, which serve not only to admit heating water from the boiler to the heater, but also to discharge such water from the heater into the boiler after a desired heat transfer between the boiler water and the domestic water supply has taken place. This may be accomplished by connections constructed more particularly as illustrated in Figure 3, which connections are of such nature that the bottom wall 18 thereof intersects the shell of the heater 4 substantially at its lowest point, while the opposite wall 19 intersects the heater shell at substantially its highest point. In actual practice it has been found that such a construction produces an efficient and continuous circulation of boiler water from the water chamber into and out of the heater 4 so that a heat transfer is continuously taking place.

It will be apparent to those skilled in the art that a construction as described permits the use of connections 18 which may be easily welded onto the shell 4 at the desired points and which may be similarly welded directly onto the boiler. This not only facilitates the manufacture of the heater but also its installation, it being unnecessary to provide a multiplicity of special connections or fittings for the reception of the heater.

For venting the water space of the heater 4, it may be provided with a vent 20 leading into the vapor space of the water chamber within the boiler.

The connections 17 are preferably located adjacent the water level in the boiler for the reason that such water is at substantially the highest temperature and thereby effects a better interchange.

In Figures 4 and 5 there is illustrated a slightly modified embodiment of the invention, in which parts corresponding to the parts already described are designated by the same reference characters having, however,

a prime affixed thereto. In this embodiment, the boiler 2' is illustrated as comprising a plurality of sections 21 and the heater 4' is shown as having an individual circulating connection 17' with each of the sections. The connections 17' differ slightly from the connections 17 before described with respect to their upper walls 19', but the lower walls 18' thereof are disposed substantially in the plane of the bottom of the heater shell 4', this construction also producing a circulation of the character set forth.

By connecting the heater 4' to each of the sections 21, the heater serves as an intersectional circulating means for the various boiler sections, and thereby tends to maintain the water in all of the sections at substantially the same temperature. In ordinary sectional boiler installations, there is no connection between the various sections at or adjacent the water level, so that it is possible to have a marked difference between different sections. In accordance with my invention, the interconnection of the heater to each section precludes such a temperature difference. In this manner, steaming of the water in some of the sections during conditions of low load on the boiler and at times when the installation is being intermittently fired, is prevented. This is accomplished by uniformly drawing off substantially the hottest water from all of the boiler sections and abstracting heat therefrom for heating the domestic water supply, after which the relatively cooler water is returned to the boiler.

I have found that single circulating connections of the character herein indicated may be utilized to replace the dual connections, heretofore considered necessary, if and when the bottom wall of the connections is so disposed as to lie substantially in the plane of the lower wall of the heater shell in such manner as to prevent any pocketing of water within such shell. Any change in the relative position of these parts, particularly such as would result from an upward movement of the bottom wall of the connections, interferes very materially with the desired circulation, and any substantially upward displacement will entirely prevent such circulation through a single connection.

The simplicity of the structures herein disclosed is such that they may be readily attached to any existing or new boiler installation, with a minimum of labor, at a minimum cost, and with a minimum number of fittings. This is highly advantageous inasmuch as in many cases the sale of a domestic water heating supply of the general character herein contemplated is prevented by the fitting requirements of the particular heater under consideration.

Other advantages arise from the utilization of single connections between the boiler and the heater, which connections serve to

provide a water flow therethrough in opposite directions.

While I have herein illustrated certain preferred embodiments of the present invention, it will be apparent that changes in the specific construction herein illustrated and described may be made without departing either from the spirit of the present invention or the scope of my broader claims.

10 I claim:—

1. In combination, a boiler having a water chamber, a water heater disposed laterally of said boiler slightly below the water level thereof, and a water circulating connection between said chamber and said heater, said water heater being of the type wherein the circulated boiler water acts as a heating medium for the water to be heated in said heater, said connection exclusively communicating with said heater in such manner that the lower portion of the connection is effective for circulating water through the bottom of said heater and serving in itself both as a water inlet and a water outlet for the circulation of water between said boiler and heater, the lower portion of said connection lying in a plane no portion of which remote from the boiler lies below the point of communication of the bottom of the connection 30 with the boiler.

2. In combination, a boiler comprising a plurality of sections each having a water chamber, a water heater disposed laterally of said boiler slightly below the water level thereof, and a single opening dual flow circulating connection between each of said chambers and said heater, said water heater being of the indirect type utilizing boiler water as the heating medium, said connections each communicating exclusively with said heater in such manner that the flow through the bottom of the connection is to the boiler.

3. In combination, a boiler comprising a plurality of sections each having a water chamber, a water heater disposed laterally of said boiler adjacent and slightly below the water level of said chamber, and a single opening dual flow circulating connection between each of said chambers and said heater, said water heater being of the indirect type utilizing boiler water as the heating medium, said connections each communicating exclusively with said heater in such manner that the flow through the bottom of the connection is to the boiler.

In testimony whereof I have hereunto set my hand.

ROBERT L. BLANDING.
